J. P. WILLIAMS

FOOT RAIL CONTACTOR FOR ELECTRIC BURGLAR ALARM SYSTEM

Filed April 8, 1925

51 Inventor,
John P. Williams,
BY J. H. Littell,
ATTORNEY.

UNITED STATES PATENT OFFICE.

JOHN PRITCHARD WILLIAMS, OF BAYSIDE, NEW YORK, ASSIGNOR TO DUPLEX ELECTRIC COMPANY, OF NEW YORK, N. Y., A CORPORATION OF DELAWARE.

FOOT-RAIL CONTACTOR FOR ELECTRIC BURGLAR-ALARM SYSTEMS.

Application filed April 8, 1925. Serial No. 21,477.

This invention relates to foot-rail contactors for electric burglar-alarm systems, and it comprises an improved mechanism of this type embodying the characteristics of that

5 genus of contact mechanisms of this character which was presented in my previous Patent No. 1,146,294, of July 13, 1915.

Such foot-rail contact mechanisms are designed to provide an operative service in 10 which contact of the foot at any portion of the longitudinal extent of an operating bar or member will cause the actuation of an alarm or signal in a connected electric alarm system, thus enabling instant location by the

15 operator of the means for making contact and obviating the uncertainty of finding separate push buttons or other contact devices which afford but a small area for operative actuation or which involve contact

20 units in relatively isolated positions, and for this purpose the new genus or type of foot-rail contactor mechanism as presented in my previous patent provided an extended pivotally-mounted operating bar or rod of a lon-

25 gitudinal extent covering the length of the desired operating area and adapted by its movement when pressed upon at any portion of its length to actuate a plurality of contact means connected with the electric 30 alarm system.

Foot-rail contactor mechanisms of the genus above set forth were designed for and are employed in what are commercially designated "daylight" hold-up alarm systems, and are installed in banks or other protected locations and positionally mounted upon the floor in longitudinal relation to a cashier's cage or counter or in other desired 35 positions, whereby when a burglarous hold-up occurs, and the hands of the official or operator must be held up, the extended operating bar or member can be instantly located with the foot at some point of its longitudinal extent and pressed to operate to cause 40 the actuation of the alarm.

45 These foot-rail contactor mechanisms are preferably mounted in units of desired length, and such units may be successively mounted to afford a continuous operating 50 length of any desired extent, and may be positioned at any desired point or in any

condition of mounting which will permit of the actuation of the extended operating bar or member by pressure exerted at any point thereon.

55 The object of my present invention is to provide improvements in the genus type of foot-rail contactor mechanism as above referred to, whereby a more convenient and effective and positive operation is secured 60 and accidental or unintended actuation of the extended operating bar or member is entirely precluded. A further object of my improvements is to provide a contactor mechanism of this class which will possess 65 advantages in point of simplicity in construction, range of operation, variability in type of signals or alarms actuated by the contactor mechanism, normal maintenance of operating parts, effectiveness, and general 70 efficiency.

In the drawings I have illustrated one unit of my improved foot-rail contactor mechanism, and—

75 Figure 1 is a front view thereof, partly in section, as mounted upon the floor.

Fig. 2 is a top or plan view, partly in section.

Fig. 3 is a vertical cross-section on the line 3—3, Fig. 1.

80 Fig. 4 is a vertical cross-section, on the line 4—4, Fig. 1.

Fig. 5 is a horizontal sectional view on the line 5—5, Fig. 1, looking upwardly from the position shown in Fig. 1.

85 Fig. 6 is a detail horizontal section, on an enlarged scale, on the line 6—6, Fig. 4, showing contact means which are actuated by the extended operating bar.

Fig. 7 is a diagrammatic view showing the 90 alarm-system circuit connections with the improved foot-rail contactor mechanism, whereby variable or differential signals or alarms may be actuated from respective contact means under one movement of the extended operating bar which actuates the plurality of contact means.

95 Corresponding parts in all the figures are denoted by the same reference characters.

Referring to the drawings, the body of 100 the improved foot-rail contactor unit as herein illustrated consists of a top plate, 14,

a rear plate, 15, extending downwardly therefrom, and end plates, 16—16, extending forwardly, said plates forming a body housing. Said end plates preferably have 5 their front edges recessed or curved inwardly, as at 17, intermediately of the top and bottom, to open up the body space beneath the top plate, into which the foot is projected. A bottom plate, 18, is also preferably 10 employed, extending horizontally between the end plates and forwardly of the rear plate, but said flat bottom plate is not essential to the body construction and is only for strengthening purposes and may 15 be eliminated or its front edge may be cut away or curved inwardly to reduce its area, as shown in dotted lines in Fig. 2, if desired. The top surface of the top plate 14 is preferably inclined downwardly and forwardly, as shown, to afford a convenient 20 foot rest when the foot-rail contactor device is mounted in operative position upon and above the floor. Such mounting and securing of the body structure may be effected 25 in any suitable or desired manner, and I have herein illustrated one construction for this purpose, in which the bottom edges of the end plates 16 have a laterally extending flange, as at 19, through which securing 30 screws, 20, pass into the floor, 21.

At the top of the body, immediately beneath the top plate 14, supplementary casings or housings, 22, are provided at a plurality of desired points and respectively 35 carry contact means in circuit connection with the alarm system, said housings being suitably secured in position, preferably by connection with the end plates, as at 23. The housings 22 preferably have an open 40 top, which is closed by the under surface of the top plate 14, and comprise side walls, 24, and a bottom, 25, in which latter is provided a slot, 26, of suitable length extending in a plane from front to rear.

45 Any suitable or adapted contact means may be carried by the respective supplementary housings 22, but I preferably employ the construction as herein shown, in which two opposite springs plates, 27—27, are mounted 50 in insulated status and respectively have a terminal end, as at 28, which ends of the two plates are in opposite normally-separated position, in a plane coincident with the front portion of the bottom slot of the casing or 55 housing 22, and are adapted for contact operation by the action of the extended operating bar of the foot-rail contactor mechanism.

30 designates the extended operating bar 60 or member which is comprised in the genus type of this class of foot-rail contact mechanisms. This member may be of any suitable or adapted construction, extending longitudinally of the contactor unit and operative 65 in common to all the contact means.

In the preferred construction, the extended operating-bar or member preferably consists of a cylindrical rod which is pivotally mounted and is normally positioned to extend a short distance beneath the boxes 22 70 which carry the contact means.

The pivotal mounting of the operating bar or rod is preferably upon the supplementary casings or housings 22, and in the relation of the pivotal bar to the preferred 75 construction of contact means as herein shown the housings respectively carry at their rear portion a shaft, 31, extending transversely of the box in the longitudinal plane of the operating bar and pivotally 80 mounted in the side walls of the housing, as at 32. Said shafts respectively carry a fixed laterally-projecting arm comprising one wing, 33, extending forwardly within the housing and another wing, 34, projecting 85 downwardly through the bottom slot of the housing and connected with and carrying the extended operating bar, the latter thus having its pivotal action upon the shafts 31. The action of the pivotal shafts 31 under pressure exerted upon the operating bar 30 is controlled by a coiled spring, 35, mounted upon the shaft and having one terminal, 36, in fixed connection with the housing 22 and another terminal, 37, extending 90 forwardly and over the top wing 33 of the arm which carries the operating bar. The action of the springs is thus to force the operating bar downwardly, which downward movement is limited by contact of the arm-wing 33 with the bottom of the housing, the upward movement of the operating bar being against the tension of the spring and the latter being automatically operative to return the bar to its normal downward position. The front terminal end of the arm-wing 33 is in a plane coincident with the opposite normally-separated terminal ends 28—28 of the spring contact-plates 27—27, 100 and is normally out of contact therewith, but upon upward movement of the operating bar and consequent upward movement of said wing 33 its front terminal end enters between the ends of the spring plates and thus establishes contact to close the electric alarm circuit. The contact end of the wing 33 is preferably oppositely beveled in 105 V contour, as at 38, to facilitate its contact engagement between and with the ends of the spring contact-plates in its upward 110 movement.

115 It will be understood that the action of the controlling springs 35 is to automatically return the extended operating bar 30 to its normal downward position immediately upon removal of pressure thereon, and in hold-up alarm mechanisms of this character it is especially desirable that the action be noiseless and not attract the attention of the burglar. For this desired purpose, inasmuch as the pre- 120 125 130

ferred mounting and operation of my improved foot-rail contactor mechanism is such that only an initial pressure upon the operating bar need be made and the bar at once 5 returns automatically to normal position under spring action, I provide a buffer or block, 39, preferably of elastic material, carried by the bottom of the casings or housings 22 which enclose the electric switch or 10 contact means, said buffer block being positioned immediately beneath the front terminal end of the arm-wing 33 and thus acting as a noiseless buffer when said wing returns downwardly under instant action of 15 the springs 35 when pressure upon the operating bar 30 is withdrawn.

The front of the top 14 of the body of the device is preferably extended downwardly, as at 40, to a point beneath the contact-means 20 casings or housings 22, and thus forms a front closure in front of said boxes. Said downwardly-extending front edge at the top of the body is preferably curved, as shown, forming a neat front top structure and a 25 curved top guide for the entrance of the foot to position for actuation of the extended operating bar. The lower edge of said top extension and guide preferably terminates on a plane in front of the plane of the extended operating bar when the latter is in its 30 downward normal operative position, thus forming a front closure in front of the bar, and the entire lower body space, as at 41, beneath the operating bar, is free and unobstructed and open at its front and affords 35 from its top to bottom and end to end an open unobstructed area or space for the unimpeded entrance of the foot and operation thereof within said open free space-area for 40 the actuation of the extended operating bar.

Heretofore, in foot-rail contactor mechanisms produced according to the genus hereinbefore set forth, the pivoted or hinged operating bar has been arranged to swing 45 rearwardly and upwardly, being mounted with its fulcrum or pivot at the front, so that the inward thrust of the foot actuates the bar. This condition of mounting is subject to many disadvantages, especially inasmuch as the actuation of the operating bar 50 by a direct inward thrust is liable to result in accidental or unintended operation and the giving of false alarms, and furthermore under the rearward and upward movement of the operating bar any accumulation of 55 foreign matter or rubbish within the space beneath the bar, or the entrance into said space of a broom or other implement in floor cleaning, is liable to cause the unintended 60 and accidental operative action of the bar by the inwardly-directed pressure thereon. To reduce the liability to unintended or accidental actuation of the operating bar when mounted to be moved by a direct inward and 65 upward thrust, the lower portion of the body

of the device at the open front beneath said bar has heretofore been closed, with the bar resting by gravity upon the bottom closure, leaving only a relatively small space in front of the bar for the entrance of the foot of the 70 operator, but these conditions of construction materially limit the free space or area afforded for the operative action or movement of the foot and also limit the open area at the front of the device which must be 75 found by the foot under requisite conditions of instant operation under a burglarous attack, the open front afforded for insertion of the foot being restricted to a comparatively small or narrow space existing between the 80 closed and obstructed bottom portion of the body and the inwardly and upwardly swinging operating bar.

In my improved construction, as herein set forth, these disadvantages and conditions above referred to are entirely obviated, and accidental or unintended actuation of the extended operating bar is precluded, the bar being mounted to swing forwardly and upwardly, whereby any direct inward 85 thrust or pressure against the bar is met by the stationary position thereof and the bar cannot be moved upon its pivotal mounting except by pressure in a counter direction to cause its movement forwardly and upwardly. Thus, any broom or implement entering the open front of the body of the device and striking against the extended operating bar is met by the stationary position and the fixed resistance of the bar itself, and 90 any accumulation of foreign matter within the lower portion of the open body likewise is inactive in any effect upon the operative action of the bar which can only move in a forward and upward direction. These 95 conditions of improved mounting thus enable the provision of a free and unobstructed operative space or area throughout the whole lower portion of the body of the device beneath the extended operating bar, 100 producing a wide-area open front for the reception of the foot and the desired movement thereof within the body of the device for the bringing of the toe of the foot in rear of the bar and the exertion of pressure thereon towards the front of the device and thus forwardly upon the bar to actuate it in an arc of movement forwardly and 105 upwardly.

The structural mechanism of my improved foot-rail contactor is adapted to operate upon any type of circuit connection, whether an open or closed circuit or combination of open and closed circuits, extending 110 from the contact means in the casings or housings 22 to the alarm or signal of the burglar alarm system, as will be readily understood, and the specific type of contact means which are actuated by the extended 115 operating bar may be of course varied with 120

in the range of the various switch mechanisms or well known equivalent contact means in the electrical art. It will also be understood that the series or plurality of 5 respective contact means carried by the casings or housings 22, and which are actuated in common by the one movement of the extended operating bar 30, may in their electrical connection be in multiple or in parallel 10 or in series as desired, according to the arrangement of conductors in the circuit connecting the respective contact means, whereby the one movement of the extended operating bar will actuate all of the respective contact means or certain units thereof or variably 15 operate the respective contact means in connection with variable signals or alarms or conditions in the connected burglar-alarm system.

20 I have herein shown one preferred type of electric circuit connection between the respective contact means and the alarm system, the respective contact means being connected in multiple and all operated simultaneously by one movement of the extended operating bar, it being also understood that in any conditions of movement of the operating bar if only one or less than all of the contact means were actuated the alarm or 25 signal would be given through the circuit. In the circuit arrangement just noted, two insulated conductor wires, 42—42, are respectively connected to the respective spring contact plates 27—27 of each contact means, 30 and extend outside the casings or housings 22 longitudinally between the respective contact means, as at 43, said conductors being preferably carried in a cable or conduit located immediately beneath the top plate 14 of the body of the device and secured thereto. The terminals of said insulated conductors 42—42 extend respectively to insulated binding posts, 44, carried 35 outside of the end wall of the contact-means 40 housings 22, and connected with said binding posts are the two insulated circuit conductor wires, 45—46, of the burglar alarm system, these latter conductors being preferably carried in a cable or conduit extending 45 through the rear wall or plate 15 of the body of the device and from thence downwardly to a pull box, 47, located beneath the floor under the foot-rail contactor mechanism, and are carried from thence through 50 the circuit of the burglar alarm system.

55 I have illustrated in Fig. 7 an arrangement of alarm-system circuit connections with my improved foot-rail contactor mechanism in conditions where it is desired to actuate by one movement of the extended operating bar alarms or signals of respective different types or character and respectively in circuit connection with the respective contact means which are operated by said bar. In this arrangement of circuits each dif-

ferential signal or alarm is in circuit connection with the respective contact-means in the respective casings or housings 22 by which it is actuated. Thus, in the diagrammatic illustration, the system conductors 45 70 and 46 extend from one of the housings 22 in a normally-open circuit as follows: the conductor wire 45 to one side of a battery or source of electrical energy, 48, and from the other side of the battery to the frame of 75 a normally-open automatic drop, 49, and the other conductor wire 46 extends through an annunciator, 50, to the coils and frame of the automatic drop, and from the contact, 51, of the automatic drop a connecting conductor wire, 52, extends to and through a signal device (as, for instance, an illuminating electric bulb or lamp), 53, and back to connection with the other conductor wire 45 80 in front of the battery. From another of the 85 housings 22 conductor wires 45 and 46 extend to and through another corresponding or similar circuit including a different alarm or signal device, as, for instance, an electric bell, 54. In the operation of the circuits arranged as just indicated, the burglar-alarm circuit remains open through the automatic drop 49, and the circuit constituted by the conductor wires 45—46 forming the connection between the foot-rail contactor mechanism and the burglar-alarm circuit is also 90 open at the switch formed by the spring contact-plates 27 of the contact means, the extended operating bar being in its downward position. Then, when the operator actuates 95 the operating rod of the foot-rail contactor mechanism to move it forwardly and upwardly, the circuit is closed at the switch formed by the spring contact-plates 27 and through the conductors 45—46 connected therewith. The current then passes from 100 one pole of the battery 48, through the conductor 45, and across the switch contacts 27, to and through the conductor 46 and annunciator 50 and the coils and frame of the 105 automatic drop 49 and from thence through the conductor 45 back to the opposite side of the battery. This completes a circuit across the automatic drop and energizes it, 110 which through operation of its armature causes its hinged frame plate to drop to the contact 51, and as soon as this contact is made the current passes through conductor 52 and the signal or alarm device, as at 115 53—54, and back to the conductor 45 at the initial side of the battery. The signal or alarm device is thus actuated by the current passing from one side of the battery through the conductors 45 and 52, and through the 120 signal or alarm device to the contact 51 of the automatic drop and through the hinged frame plate thereof and conductor 45 back to the opposite side of the battery. This signal 125 circuit is maintained, and the signal or alarm device is under continuous actuation until 130

the circuit is opened by again returning the automatic drop 49 to normal open position in which the contact 51 is again opened.

Thus, it is merely necessary to actuate the operating bar or member 30 of the foot-rail contactor mechanism in a forward and upward movement to close the switch formed by the contact-plates 27, when pressure upon said bar can be released and the bar automatically returns to its normal position by action of the spring 35, as only an instant action of the operating bar is required to close the circuit of the connected alarm system through the automatic drop 49 and the energizing of the latter causes the instant closing of the circuit through the signal or alarm device and the continuous actuation thereof after the pressure has been removed from the operating bar 30 and it has resumed its normal downward position and until the automatic drop is again opened as desired.

My improved foot-rail contactor mechanism is thus adapted for such circuit connection with the alarm system that the extended operating bar or member is in normal operative position at all times when the device is in use, only an instant pressure thereon being required to cause actuation of the alarm; after which the operating bar returns to normal position and the continuous actuation of the alarm is maintained until shut off.

It is obvious that the improved contactor mechanism, as produced by my invention, may be mounted in any desired position, as for upward pressure or downward pressure or lateral pressure upon the operating bar or member, and located as desired for pressure action by the foot or hand of an operator.

I do not desire to be understood as limiting myself to the detail construction and arrangement of parts as herein shown and described, as it is manifest that variations and modifications therein may be resorted to, in the adaptation of my invention to varying conditions of use, without departing from the spirit and scope of my invention and improvements. I therefore reserve the right to all such variations and modifications as properly fall within the scope of my invention and the terms of the following claims.

Having thus described my invention, I claim and desire to secure by Letters Patent:

1. A foot-rail contactor mechanism of the class described, comprising a body structure constituted by a housing having a top and a rear and end walls, supplementary casings or housings separately located and carried at the under side of said top wall, electrical contact means respectively carried by said separate casings or housings, and an operating bar pivotally mounted within the body

structure and extended longitudinally of said supplementary casings or housings and operative in its swing to actuate the respective contact means carried by said spaced supplementary casings or housings. 70

2. A foot-rail contactor mechanism of the class described, comprising a body structure constituted by a housing having a top and a rear wall and a relatively flat bottom plate, supplementary casings or housings separately located and carried at the under side of said top wall, electrical contact means respectively carried by said separate casings or housings, and an operating bar pivotally mounted within the body structure and extended longitudinally of said supplementary casings or housings and operative in its swing to actuate the respective contact means carried by said spaced supplementary casings or housings. 75

3. A foot-rail contactor mechanism of the class described, comprising a body structure having a top wall, electrical contact means carried at the under side of said top wall, an operating bar pivotally mounted within the body structure and depending beneath said top wall and operative in its swing to actuate said contact means, and an extension forming a front top closure and extending downwardly from said top wall to a point in front of the plane of the operating bar when the latter is in its downward normal position and constituting a front closure in front of the bar, said front extension being curved downwardly and inwardly and constituting a top guide for the entrance of the foot into position back of the closure in front of the operating bar. 90

4. A foot-rail contactor mechanism of the class described, comprising a body structure having a top wall, supplementary casings or housings carried at the under side of said top wall, electrical contact means carried by said supplementary casings or housings, an operating bar pivotally mounted within the body structure and operative in its swing to actuate the contact means carried by said casings or housings, and an extension forming a front top closure and extending downwardly from said top wall to a point beneath said contact-means casings or housings and constituting a front closure in front of said housings. 105

5. A foot-rail contactor mechanism of the class described, comprising a body structure having a top wall, supplementary casings or housings carried at the under side of said top wall, electrical contact means carried by said supplementary casings or housings, an operating bar pivotally mounted within the body structure and operative in its swing to actuate the contact means carried by said casings or housings, and an extension forming a front top closure and extending downwardly from said top wall to 110

115 120 125 130

- a point in front of the plane of the operating bar when the latter is in its downward normal position, said front extension constituting a front closure in front of said supplementary casings or housings and the operating bar and being curved downwardly and inwardly to form a top guide for the entrance of the foot into position back of the closure in front of the operating bar.
- 10 6. A foot-rail contactor mechanism of the class described, comprising a body structure having a top wall, electrical contact means carried at the under side of said top wall, an operating bar mounted within the body structure and depending beneath said top wall and pivoted to swing in an arc of movement forwardly and upwardly to actuate said contact means, and means for retaining the operating bar against inward or rearward movement, whereby any direct inward thrust or pressure against the operating bar is met by a fixed or stationary position thereof, the entire lower body space or area of the body structure beneath the operating bar being open and free or unobstructed to provide an unobstructed bottom area or space for the unimpeded operation of the foot to actuate said bar in its forward and upward swing.
- 20 7. A foot-rail contactor mechanism of the class described, comprising a body structure having a top wall, supplementary casings or housings carried at the under side of said top wall, electrical contact means carried by said casings or housings, an operating bar pivotally mounted and extending within the body structure beneath the operating bar pivotally mounted and extending within the

body structure and having an extension operatively projective with relation to said contact means to actuate the same in the swing of the bar, and means comprised in the supplementary casings or housings to limit the movement of the operating bar.

8. A foot-rail contactor mechanism of the class described, comprising a body structure having a top wall, supplementary casings or housings carried at the under side of said top wall, electrical contact means carried by said casings or housings, an operating bar pivotally mounted and extending within the body structure and having an extension operatively projective with relation to said contact means to actuate the same in the swing of the bar, and spring control-means comprised in the supplementary casings or housings and operative to return the operating bar to normal position.

9. A foot-rail contactor mechanism of the class described, comprising an open-front housing, electrical contact means carried within the top portion of said housing, an operating bar extending within said housing and pivotally mounted to swing in an arc of movement forwardly and upwardly towards the front of the housing and in its swing actuate said contact means, and means for maintaining a fixed position of said operating bar against movement or actuation by an inward thrust or pressure from the front of the housing.

In testimony whereof I have signed the foregoing specification.

JOHN PRITCHARD WILLIAMS.
